US00D982478S

(12) **United States Design Patent** (10) Patent No.: **US D982,478 S**
(45) Date of Patent: **** Apr. 4, 2023**

(54) **BUCKLE**

(71) Applicant: **Shenzhen Fengtouniao Technology Co., Ltd.**, Shenzhen (CN)

(72) Inventor: **Weiwei Qu**, Fengcheng (CN)

(**) Term: **15 Years**

(21) Appl. No.: **29/830,512**

(22) Filed: **Mar. 14, 2022**

(51) LOC (14) Cl. **02-07**

(52) U.S. Cl.

USPC **D11/200**

(58) **Field of Classification Search**

(57) **CLAIM**

The ornamental design for a buckle, as shown and described.

DESCRIPTION

FIG. 1 is a front perspective view of a buckle showing my new design;

FIG. 2 is a front view thereof;

FIG. 3 is a back view thereof;

FIG. 4 is a left-side view thereof;

FIG. 5 is a right-side view thereof;

FIG. 6 is a top view thereof; and,

FIG. 7 is a bottom view thereof.

The broken lines in the drawings depict portions of the buckle that form no part of the claimed design.

1 Claim, 5 Drawing Sheets
